UNITED STATES PATENT OFFICE.

GEORGE H. HERRNECKER, OF HORNELL, NEW YORK.

REFLECTOR.

No. 897,464.

Specification of Letters Patent.

Patented Sept. 1, 1908.

Application filed November 25, 1907. Serial No. 403,730.

To all whom it may concern:

Be it known that I, GEORGE H. HERRNECKER, a citizen of the United States, residing at Hornell, in the county of Steuben and 5 State of New York, have invented new and useful Improvements in Reflectors, of which the following is a specification.

This invention relates to reflectors particularly adapted for use in connection with locomotive furnace doors, and the object thereof 10 is to provide in a manner as hereinafter set forth a reflector, whereby there is obtained the full lighting power of the furnace to assist the fireman while at work so that the ordinary 15 fireman's torch can be dispensed with.

A further object of the invention is to provide a reflector in a manner as hereinafter set forth which is readily attached to a locomotive furnace door, simple in construction, 20 strong, durable, efficient in its use, and comparatively inexpensive to manufacture.

With the foregoing and other objects in view, the invention consists in the novel construction, combination and arrangements of 25 parts hereinafter more specifically described and illustrated in the accompanying drawings, wherein is shown the preferred embodiment of the invention, but it is to be understood that changes, variations and modifications 30 can be resorted to which come within the scope of the claims hereunto appended.

In describing the invention in detail, reference is had to the accompanying drawings, wherein like reference characters denote corresponding 35 parts throughout the several views, and in which:—

Figure 1 is a front elevation of a locomotive furnace door showing the adaptation therewith of a reflector in accordance with this invention. Fig. 2 is a vertical sectional view 40 of the door, also showing the reflector in longitudinal section. Fig. 3 is an inverted plan of the reflector, also showing the door in sectional plan. Fig. 4 is a perspective view 45 of the body portion of the reflector. Fig. 5 is a perspective view of the cut-off. Fig. 6 is a detail of the pivot for the cut off and the means for maintaining the cut off from movement after it has been shifted to open 50 or to closed position.

Referring to the drawings in detail, 1 denotes a locomotive fire door which is hinged to a fire box as at 2. 3 denotes the door handle, and 4 a latch adapted to receive the 55 free end of the handle for maintaining the door closed. The foregoing elements are of

known construction and are shown by way of example so that the adaptation of a reflector in accordance with this invention with a locomotive fire box door can be readily understood. The door 1, however, is provided with an opening 5 through which the light from the furnace escapes, the reflector being arranged in operative relation with respect to the opening so as to direct the light rays to 60 enable the fireman to see to perform his duties at night without the use of the torch employed for such purpose.

A reflector in accordance with this invention comprises a semi-cylindrical body portion 6 having longitudinally extending inverted flanges 7 which constitute seats for a semi-cylindrical reflecting member 8 which is of a length to project slightly past the inner end of the body portion 6. The member 75 8 is prevented from longitudinal movement with respect to the body portion 6 through the medium of a retaining screw 9, the latter extending through the body portion 6 and member 8, as clearly shown in Fig. 2. 80

The body portion 6 at its inner end terminates in a semi-cylindrical flange 10 provided with openings 11 through which extend hold-fast devices 12 for securing the body portion to the door 1. The flange 10 surrounds the 85 opening 5 and is provided with a seat 13 which receives a semi-oval-shaped disk 14 which constitutes means for closing the opening 5, thereby cutting off the light rays. The disk 14 and its lower end project below 90 the edge of said opening as well as below the lower edge of the body portion 6 and one side of said projecting portion is formed with a lug 15 which extends at right angles with respect to the disk. The lug 15 has formed 95 integral therewith a circular disk 16 extending in parallelism with respect to the outer face of the door 1 and which has its inner face provided with a series of notches 17. Projecting outwardly from the lower portion 100 of the disk 16 is a bevel-shaped extension 18 which is formed integral with an outwardly inclined handle 19, the latter at its inner end being formed integral with the outer face of the disk 14 as at 20. 105

The flange 10 at one end is provided with an opening 21 and further provided with a pair of vertically extending lugs 22 which are arranged in parallelism with respect to each other and terminate at the edge of the 110 opening 21. The disk 16 is adapted to abut against the apertured end of the flange 10

and the grooves 17 in the disk 16 are adapted to receive the lugs 22. The disk 16 is pivotally connected to the flange 10 through the medium of a headed bolt 23 which extends 5 through the opening 21 and an opening 24 formed in the disk 16, the head of the bolt being seated in a counter-sunk portion 25 formed in the inner face of the flange 10. The outer end of the bolt 23 is screw-threaded as at 26, the said screw-threaded end carrying a pair of nuts 27, 28. Surrounding the bolt 23 and interposed between the nut 28 and the outer face of the disk 16 is a coil compression spring 29, the function of which 10 is to maintain the disk 16 in engagement with the flange 10 and furthermore maintain the lugs 22 in the grooves or notches 17. The tension of the spring 29 can be adjusted by manipulating the nuts 27, 28. The 15 spring 29 further constitutes a means for holding the cut-off 14 in a closed or open position as the case may be. The cut-off or disk 14 is shown in open position in Fig. 1 and in closed position in Fig. 2 and Fig. 3. 20 The engagement of one of the lugs 22 with one of the grooves or notches 17 is clearly 25 shown in Fig. 3.

When the disk 14 is moved to the position shown in Fig. 1, the light rays escape through 30 the opening 5 and are reflected by the member, consequently enabling the fireman to see while performing his work and without necessitating the employment of the ordinary fireman's torch. The lugs 22 in connection with the notches or grooves 17 provide means for controlling the light rays, 35 that is to say the cut-off 14 can be adjusted to positions partially closing the opening 5 so that the volume of light rays from the furnace can be increased or diminished as is desired. If the light is too intense, by partly closing the cut-off the light can be diminished. The spring 29 will maintain the cut-off 40 14 in its adjusted position.

45 By providing a reflector in accordance with this invention, it overcomes the dangerous practice of utilizing a burning torch while the engine is in motion, as the glare being reflected from the glass of the front 50 door of the engine cab makes it impossible to detect danger signals ahead without looking out of the side cab window which is very dangerous, especially in stormy weather.

The reflector in accordance with this invention will also enable one to dispense with the burning of the torch while the fireman is preparing his fuel and firing his engine without necessitating any expense, as the light rays are obtained from the fire box of the 55 furnace.

60 What I claim is:—

1. A reflector for the purpose set forth comprising a regulatable cut-off, a body portion provided with an interiorly arranged reflecting member, a regulatable cut-off exte-

riorly of and at one terminus of the body portion and means whereby said body portion and cut-off can be maintained in proximity to a source of light.

2. A reflector for the purpose set forth 70 comprising a body portion having an interiorly arranged reflecting member and terminating at one end in a flange, a cut-off, and means for pivotally and adjustably connecting the cut-off to said flange, said cut-off 75 when in closing position arranged at one end of the body portion.

3. A reflector for the purpose set forth 80 comprising a body portion, a reflecting member supported therein, means extending through the body portion to prevent shifting of said member, a cut-off, and means for pivotally and adjustably connecting the cut-off 85 with the body portion at one terminus thereof.

4. A reflector for the purpose set forth 90 comprising a body portion, a reflecting member secured therein, a cut-off, and means for pivotally and adjustably connecting the cut-off with the inner terminus of the body portion, said cut-off arranged exteriorly of the 95 inner terminus of the body portion.

5. A reflector for the purpose set forth 100 comprising a flanged body portion, a reflecting member secured therein, means extending through the flange whereby said body portion can be maintained in close proximity 105 to a source of light, a cut-off provided with a handle, and a pivotal connection between said handle and said flange.

6. A reflector for the purpose set forth 110 comprising a flanged body portion, a reflecting member secured therein, means extending through the flange whereby said body portion can be maintained in close proximity 115 to a source of light, a cut-off having a handle, a pivotal connection between said handle and said flange, and means whereby said cut-off can be adjusted to and maintained in various positions.

7. A reflector for the purpose set forth 120 comprising a body portion provided with a reflecting medium, a flange arranged at one end of the body portion and provided with a seat, a cut-off adapted to engage said seat, 125 and means for pivotally connecting the cut-off to said flange.

8. A reflector for the purpose set forth comprising a body portion provided with a reflecting medium, a flange arranged at one end of the body portion and provided with a seat, a cut-off adapted to engage said seat, means for pivotally connecting the cut-off to 130 said flange, and an outwardly inclined handle formed integral with the cut-off and arranged at a point below the body portion.

9. A reflector for the purpose set forth comprising a body portion provided with a reflecting medium, a flange arranged at one end of the body portion and provided with a 135

seat, a cut-off adapted to engage said seat, means for pivotally connecting the cut-off to said flange, and means for maintaining said cut-off in various adjusted positions.

- 5 10. A reflector for the purpose set forth comprising a body portion provided with a reflecting medium, a flange arranged at one end of the body portion and provided with a seat, a cut-off adapted to engage said seat, 10 means for pivotally connecting the cut-off to said flange, an outwardly inclined handle formed integral with the cut-off and arranged at a point below the body portion, and means for maintaining said cut-off in various 15 adjusted positions.

11. The combination with a support having an opening for the escape of light rays, of a reflector secured to said support in proximity to said opening, said reflector having a pivoted cut-off for closing said opening and 20 further having means for maintaining said cut-off in various adjusted positions.

In testimony whereof I have hereunto set my hand in presence of two subscribing witnesses.

GEORGE H. HERRNECKER.
